UNITED STATES PATENT OFFICE.

ELIAS KIRSCHENBAUM, OF PHILADELPHIA, PENNSYLVANIA, ASSIGNOR TO ELTSAC COLORING PROCESS CORPORATION, A CORPORATION OF NEW YORK.

PROCESS OF PRODUCING DYED FABRICS.

No Drawing.

Application filed October 8, 1923. Serial No. 667,413.

To all whom it may concern:

Be it known that I, ELIAS KIRSCHENBAUM, a citizen of the United States, residing at Philadelphia, in the county of 5 Philadelphia and State of Pennsylvania, have invented new and useful Improvements in Processes of Producing Dyed Fabrics, of which the following is a specification.

10 This invention relates to a process of producing dyed fabrics and is intended to be applicable to all manners of fabrics including woven, knitted, and braided textiles, and any form of fabric in which a process 15 of the nature could be utilized.

The object of the invention is to produce fabrics of one or more colors by impregnating certain of the threads, yarns or other portions of the fabric prior to the time of 20 weaving, knitting or braiding, with a superabundance of dye material which material is afterwards released so as to dye the adjacent threads, yarns, or other portions of the fabric when completed so as to form 25 all manner of designs and mottled effects.

Another object is to produce dyed goods in a manner avoiding the present costly methods of effecting these results.

With these and other objects in view the 30 process consists in certain operations, the nature and sequence of which will be hereinafter fully explained and will be particularly pointed out in the claims hereunto annexed.

35 In carrying out the present process, I have had in mind particularly, the making and dyeing of artificial silken tape and braid wherein it is very difficult to pre-dye certain of the materials which are interwoven. In carrying out the process, certain 40 of the threads which are of such nature as to readily adapt themselves to dyeing prior to being worked up into the fabric, are filled with a considerable quantity of dye-stuff, the quantity being filled according to 45 the shade and effect desired. I then work up this dyed material together with the other material which is light colored, white or in its natural color, and I then subject 50 the entire fabric to a moistening treatment, either by placing it in a bath or by subjecting it to jets of steam or to other moistening agencies. If it is then desired that the 55 color should be fixed, the goods may be treated with a mordant.

It is to be remembered that in certain sorts of fabrics, ribbons, braids, gimp threads and bese threads are oftentimes woven into the fabric so as to form welts and other peculiarities in the fabric. If 60 these various portions of the fabric have been pre-dyed according to the above mentioned process, the resulting fabric after wetting will have a very peculiar and ornamental effect which is also contemplated by 65 the present invention.

It is also desired to point out that by excess dyeing of either part of the warp or part of the woof threads or part of both, and thereafter effecting the making up of 70 the material and the moistening of the same, striped and checkered patterns may be obtained. It is also obvious that a number of different colors can be used in this way and can be run into each other in which 75 case they would blend and harmonize with remarkable smoothness. Under these circumstances, it is contemplated that a number of varying forms of designs and fabrics can be produced by utilizing the dyeing 80 threads either for the entire warp, the entire filling or weft, for sections of either, for sections of both, for sections of the warp in knitted fabrics, and for sections of 85 round or horizontally knitted fabrics. Likewise, for sections of braid without warp, for sections of the warp, or entire warp of the braids, and for sections of various colors in any form of fabric.

As to the wetting operation, this may be 90 as above stated, either with plain water or with steam or if found more effective on the dyes, then any form of suitable mechanical agent may be utilized for this purpose. According to the amount of dye 95 which is placed in the fabric and according to the action which is permitted at the time of wetting, the fabrics may be turned out either in pattern, in mottled effects, or in plain solid colors.

100 It is also contemplated that the dye may be printed on the threads prior to the making up of the fabric, and then after the fabric is woven or otherwise made up, the wetting process will bring out the variously 105 located color or colors so as to produce a mottled effect.

What I claim is:—

110 1. The herein described process of producing dyed fabrics which consists in manu-

facturing a fabric partly from undyed material and partly from material carrying an excess of dye and of then subjecting the entire fabric to a wetting agent.

5. 2. The herein described process of producing dyed fabrics which consists in dyeing certain threads with an excess of dye material, then weaving or otherwise uniting said threads with other undyed threads to form a fabric, and then subjecting said fabric to a moistening agent.

10. 3. The herein described process of producing dyed fabrics which consists in dyeing certain threads with an excess of dye

material, then weaving or otherwise uniting 15 said threads with other undyed threads to form a fabric, and then subjecting said fabric to the action of a mordant.

4. The herein described process of producing dyed fabrics which consists in manu- 20 facturing a fabric partly from material carrying an excess of dye and partly from material not carrying an excess of dye, and of then subjecting the entire fabric to a wetting agent. 25

In testimony whereof I affix my signature.

ELIAS KIRSCHENBAUM.
